UNITED STATES PATENT OFFICE.

GERRIT LOUIS GOEDHART, OF THE HAGUE, NETHERLANDS.

APPARATUS FOR DETACHING MINES FROM THEIR ANCHORS.

1,287,674.

Specification of Letters Patent. Patented Dec. 17, 1918.

Application filed April 11, 1918. Serial No. 228,062.

To all whom it may concern:

Be it known that I, GERRIT LOUIS GOEDHART, a subject of the Queen of the Netherlands, residing at The Hague, Netherlands, have invented certain new and useful improvements in Apparatus for Detaching Mines from Their Anchors, of which the following is a specification.

It is a well-known fact that anchored mines may be inactivated by detaching them from their anchors by means of a suitable apparatus towed through the water by a so-called mine-sweeper.

The present invention relates to an apparatus of this type which has for its object to cut through the anchoring chains of such mines. The apparatus comprises cutting-pliers whose jaws when engaging an anchoring chain are automatically closed owing to the resistance offered by said chain.

The annexed drawings illustrate an apparatus in accordance with the present invention; in these drawings:

Figure 1 shows a plan view;

Fig. 2 represents a sectional view along A—A in Fig. 1;

Fig. 3 is a sectional view along B—B in Fig. 1 and illustrates the position of an anchoring chain between the jaws of the apparatus;

Fig. 4 is a perspective view of a part for guiding the movable jaw;

Fig. 5 is a perspective view of a so-called bridge-piece;

Fig. 6 represents a perspective view of a pawl used in connection with the arrangement shown in Fig. 1;

Fig. 7 shows a plan view of part of the apparatus with a pawl arrangement of somewhat different construction.

The apparatus comprises a substantially triangular frame composed of a top plate 1 and a bottom plate 2 secured thereto at a suitable distance, the cutting-pliers being mounted between these plates. At the corners 3 and 4, the frame is connected to a towing rope 5, which is carried by supports extending from the bow and side of a ship. The frame carries a suitable floater 50, in such a manner that the apparatus during its movement through the water assumes a substantially horizontal position.

The cutting-pliers are composed of two jaws 6, 7, provided with removable knives.

The jaw 6 is secured to or integral with a yoke 8 rotatably mounted on a pivot 9 of

the frame. The other jaw 7 is rotatably connected to the jaw 6 by means of a pivot 10, and to one end of a rod 12 by means of a pivot 11, the other end of the said rod 12 being rotatably mounted on a pivot 13 of the frame. An arm 14, secured to the yoke 8 is engaged by a spring 16 connected with a hook 15 which is adjustably secured to the frame, in such a manner, that the said arm 14 always has a tendency to move the yoke 8 into the position shown in Fig. 1. In this position the yoke 8 with the cutting-pliers is held by a spring blade 17 provided with a lug 18 (see Fig. 6) having a suitably inclined face 19.

The jaw 7 is integral with a finger 20 located opposite its cutting edge in such a manner that the said members inclose a comparatively narrow mouth. For properly guiding the jaw 7 a block 22, illustrated in detail in Fig. 4, is secured between top and bottom plates 1 and 2 respectively; said block is provided with a suitable recess 21 for receiving the jaw 7, and formed so as to cause a mine anchor cable which is deflected along the rope 5 to be positively fed into the mouth of the jaw 7.

In order to avoid any clearance between the block 22 and the rope 5, which might cause a deflected mine anchor cable to be caught before it enters the mouth of the jaw 7, the frame is provided with a swivel block 24 mounted on a pivot 23 and around which the rope 5 is passed. It is obvious that the swivel block, when turning in the direction of the arrow 25, has a tendency to firmly press the rope 5 against the block 22, the pressure increasing proportionate to the tension in the rope 5.

Should a mine anchor cable engage the apparatus at a point behind the cutting-pliers, it is essential that it may glide off the apparatus without being caught; the apparatus is, therefore, provided with a bridge-piece 27 rotatably mounted on a pivot 28 near the corner 4 of the frame. Said bridge-piece is illustrated in detail in Fig. 5; in cross-section it has a U-shape, and it is engaged by spring 29 which always tends to move it into the position shown in Fig. 1, when its front end receives the jaw 6.

The operation of the apparatus is as follows:

If the rope 5 engages a mine anchor cable, the latter is deflected and glides along said rope so as to be fed into the comparatively

narrow mouth of the jaw 7. The width of said mouth is such that the mouth can receive a link of the chain only when said link lies flat as shown in Fig. 3. Now, owing to the pressure exerted by the anchor chain on the member 20 and jaw 6, the yoke 8 is pressed against the inclined face 19 of the lug 18 of spring pawl 17, so that the latter yields and the lever 8 turns about the pivot 9 through a suitable angular distance in the direction of the arrow 30. During this movement the jaws of the cutting-pliers are automatically closed owing to the eccentric rotation of the rod 12 relative to the yoke 8. 15 If the different parts are suitably dimensioned, the jaws 6 and 7 will be entirely closed and, consequently, the anchor chain cut through before the yoke 8 at the end of its circular path contacts with the frame. 20 During this movement the jaw 6 glides along the inner face of the bridge-piece 27 without its movement being interfered with thereby.

As soon as the anchor chain has been cut through, the cutting pliers, under the influence of the spring 16, return into their original position in which they are locked by the spring pawl 17, 18.

The spring pawl 17, 18 has for its object 30 to prevent the cutting-pliers from being turned in the direction of the arrow 30 under the influence of say strong currents, in order that the apparatus may only be actuated by a comparatively great resistance such as is offered by a mine anchor chain. Fig. 7 shows another construction of the pawl arrangement. This arrangement comprises a hook-shaped lever 32 rotatably mounted on a pivot 31 of the jaw 7, and having a projection 33 which, when the apparatus is inoperative, is engaged by a lug 34 on the guide-piece 22; in this position the hook 32, held by a spring 35, locks the cutting-pliers in their position shown in Fig. 1. If, 40 however, a mine anchor chain enters the mouth of the jaw 7, this chain will press the inner end of the hook 32 against the action of the spring so that the hook turns about the pivot 31 and the projection 33 disengages the lug 34, when the cutting-pliers are free to rotate about the pivot 9. After the anchor chain has been cut through, 45 the cutting-pliers return into their original position and the lug 34 reengages the projection 33 so as to again lock the apparatus.

What I claim and desire to secure by Letters Patent is:

1. In an apparatus of the type referred to, a frame adapted to be secured to a towing rope, with a cutting tool movably mounted therein and adapted to become operative when moving relative to the frame, the cutting edges of said cutting tool normally resting adjacent the point where the frame connects to the rope, whereby said

rope will act to guide a mine cable into position to be engaged by the cutting tool.

2. In an apparatus of the type referred to, the combination of a frame adapted to be secured to a towing rope, with a cutting tool 70 comprising two jaws pivotally connected together, one jaw being pivoted to the frame directly, the other through a member to which it is pivotally connected, the cutting edges of said cutting tool normally resting 75 adjacent the point where the frame connects to the rope, whereby said rope will act to guide a mine cable into position to be engaged by the cutting tool.

3. In an apparatus of the type referred 80 to, the combination of a frame adapted to be secured to a towing rope, a cutting tool comprising two jaws pivotally connected together, one jaw being pivoted to the frame directly, the other through a member to 85 which it is pivotally connected, with a member for yieldingly locking the cutting tool in its inoperative position, the cutting edges of said cutting tool normally resting adjacent the point where the frame connects to 90 the rope, whereby said rope will act to guide a mine cable into position to be engaged by the cutting tool.

4. In an apparatus of the type referred 95 to, the combination of a frame adapted to be secured to a towing rope, a cutting tool comprising two jaws pivotally connected together, one jaw being pivoted to the frame directly, the other through a member to which it is pivotally connected, with a 100 spring drawn lever which is pivotally connected to one of the jaws and which, in the inoperative position of the apparatus, with one end projects into the mouth of the cutting tool while its other end is engaged by 105 a lug of the frame.

5. In an apparatus of the type referred to, the combination of a frame adapted to be secured to a towing rope, a cutting tool comprising two jaws pivotally connected to- 110 together, one jaw being pivoted to the frame directly, the other through a member to which it is pivotally connected, with a rotatably mounted spring drawn bridge piece which in the inoperative position of the ap- 115 paratus forms a substantially rectilinear guide between the cutting tool and the rear connection for the towing rope.

6. In an apparatus of the type referred 120 to, the combination of a frame adapted to be secured to a towing rope, a cutting tool comprising two jaws pivotally connected together, one jaw being pivoted to the frame directly, the other through a member to 125 which it is pivotally connected, with a guide piece provided with a recess for receiving the movable jaw of the cutting tool and arranged so as to cause a mine anchor cable engaged by the towing rope to be positively fed into the mouth of the cutting tool. 130

7. In an apparatus of the type referred to, the combination of a frame adapted to be secured to a towing rope, a cutting tool comprising two jaws having cutting edges and pivotally connected together, one jaw being pivoted to the frame directly, the other through a member to which it is pivotally connected, with a finger secured to the movable jaw in such a manner, that a comparatively narrow mouth is formed between the finger and the cutting edge of the jaw to which the finger is secured.

8. In an apparatus of the type referred to, the combination of a frame adapted to be secured to a towing rope, a cutting tool comprising two jaws pivotally connected together, one jaw being pivoted to the frame directly, the other through a member to which it is pivotally connected, with a swivel block around which the towing rope may be passed and adapted to press said rope against the frame with a force which is proportionate to the tension of the rope.

9. In an apparatus of the type referred

to, the combination of a frame adapted to be secured to a towing rope, a cutting tool comprising two jaws pivotally connected together, one jaw being pivoted to the frame directly, the other through a member to which it is pivotally connected with a spring tending to move the cutting tool into the inoperative position, the cutting edges of said cutting tool normally resting adjacent the point where the frame connects to the rope, whereby said rope will act to guide a mine cable into position to be engaged by the cutting tool.

10. In an apparatus of the type described in claim 1, a floater carried by the frame adapted to maintain the apparatus in a substantially horizontal position when the latter is being towed through the water.

In testimony whereof I have affixed my signature in presence of two witnesses.

GERRIT LOUIS GOEDHART.
